UNITED STATES PATENT OFFICE.

THOMAS F. BOLIG, OF BELLEVUE, OHIO.

LINE-BUCKLE.

1,388,401.

Specification of Letters Patent. Patented Aug. 23, 1921.

Application filed April 23, 1919. Serial No. 292,081.

To all whom it may concern:

Be it known that I, THOMAS F. BOLIG, a citizen of the United States, residing at Bellevue, in the county of Huron and State 5 of Ohio, have invented a new and useful Line-Buckle, of which the following is a specification.

This invention relates to improvements in line buckles for double harness, the object of 10 the invention being to provide a device of this character so constructed that the so-called "dead" end of the cross line is completely inclosed, whereby there are no projecting parts to catch into fly nets, and in 15 the use of which device a minimum number of openings are required to be punched in the lines.

A further object of the invention is to 20 generally improve and simplify the construction of devices of the character set forth and at the same time provide a buckle that is highly efficient in use.

With the foregoing and other objects in 25 view, which will appear as the description proceeds, the invention consists in the novel features of construction and combination of parts which will be more fully described hereinafter and particularly pointed out in the claim.

30 In the drawings accompanying and forming part of this specification,

Figure 1 is a plan view showing my improved buckle attached to the hand and cross lines of a set of double harness, the 35 lines being shown broken away;

Fig. 2 is a longitudinal section taken on the line 2—2 of Fig. 1;

Fig. 3 is a cross section taken on the line 3—3 of Fig. 2; and

40 Fig. 4 is a cross section taken on the line 4—4 of Fig. 2.

The same characters of reference designate the same parts in the different figures of the drawings.

45 Referring to the drawings, 2 designates a hand line and 3 a cross line. My improved buckle comprises a base 4, which may be provided with openings 5 therethrough for lightening the structure, and

50 which base is adapted to underlie the lines. The base is provided at one end thereof with a loop member formed of a pair of upstanding sides 6 and a cross member 6', thereby forming an opening between the base and

55 the cross member 6' of sufficient width to accommodate both the hand line and cross

line, as shown in Fig. 2. At its opposite end the base is formed with an upstanding portion 7 spaced apart from the top cross member 8 a sufficient distance to accommodate 60 only the hand line, and this cross member is connected with the base by a pair of side members or lugs 9 merging into the base and projecting upwardly at the sides of the base, the contour of the upper edges of the 65 lugs being approximately ogee. By this construction lateral shifting of the free or dead end of the cross line 3 is prevented, and between the lugs and the upturned end of the base member a housing is provided in 70 which such free end of the line is entirely inclosed, whereby it is protected and prevented from catching in fly nets, etc. The base is provided approximately at the center thereof with a single upstanding cylindrical lug 10 adapted to engage an opening 75 in both the hand and cross lines, as shown in Fig. 2, for preventing withdrawal thereof from the buckle. By the provision of a single lug, a minimum number of perforations are necessary in the lines, and at the 80 same time such lines are securely held in the buckle.

While I have described in detail the structure herein illustrated, it is to be understood 85 that I do not thereby limit my invention to the precise features of construction shown, as I am aware that many mechanical changes and modifications may be made therein without departing from the spirit 90 and scope of the invention as set forth in the claim appended hereto.

Having thus described my invention, what I claim is:

A buckle comprising a base provided at 95 its ends with first and second terminal members disposed at right angles to the base, the terminal members having openings, the axes of which are parallel to the base, the opening in the first member terminating at 100 the base, and the opening in the second member being approximately one-half the height of the opening in the first member and terminating in spaced relation to the base thereby to form a transverse flange, side lugs 105 being formed integrally with the second member and with the base and coöperating with the transverse flange to form a pocket for one end of one of two straps, both of which extend through the opening in the 110 first member, the other of which straps extends through the opening of the second

member, the base being provided intermediate its ends with a stud located between the first and second members, the lugs terminating in spaced relation to the first member, 5 to permit the edges of the straps to be engaged by the fingers of an operator, when it is desired to remove the straps from the stud.

In testimony that I claim the foregoing as my own, I have hereto affixed my signature in the presence of two witnesses.

THOMAS F. BOLIG.
